PORTABLE ELECTRIC REFRIGERATOR

Robert G. Sheidler and Truman B. Clark, Mansfield, Ohio, assignors to The Tappan Stove Company, Mansfield, Ohio, a corporation of Ohio

Application June 13, 1952, Serial No. 293,373

9 Claims. (Cl. 62—102)

1

This invention relates to electric refrigerators which are especially adapted for military use in transport airplanes when ferrying personnel from place to place. Although the refrigerator was particularly designed for military use it is equally well adapted for civilian use.

Military transport planes vary greatly in size and capacity and are sometimes used to ferry personnel several thousand miles, and at other times to ferry personnel only a relatively short distance. Precooked meals for the personnel being transported are kept in a refrigerator aboard the plane during flight. Before taking off, the refrigerator is stocked with meals in accordance with the number of persons being flown and the distance of the flight. Sometimes food must be carried for both the outgoing and the return flight. In transport airplanes the weight and size of equipment are of prime consideration. Consequently, refrigerators therefor should be of such size as to carry only the required number of meals for a given flight, and they should be constructed as lightly as possible to give the required service.

In certain parts of the world when a military transport plane stands in the sun on the ground for only a short time the ambient temperature therein sometimes reaches 160°. Therefore refrigerators for military transport planes must be so constructed that they will operate equally well in both low ambient temperature and in extremely high ambient temperatures. They should also be so constructed that the refrigerating mechanism therefor can be quickly and easily removed as a unit and replaced with another unit in the case of damage or failure.

With the foregoing in mind we designed a mobile refrigerator of large capacity, but which is relatively small in size, which is relatively light in weight, which will operate equally well in both low and extremely high ambient temperatures, in which the refrigerating mechanism can be quickly removed and replaced as a single unit, and in which the capacity and size can be varied as desired.

Our new and improved design of refrigerator comprises generally a base section, a top section, one or more intermediate sections and an electric refrigerating mechanism of conventional type. The base section, which is mounted upon a pair of spaced parallel rails which extend out beyond one side thereof, comprises a bottom wall, a rear wall, a pair of spaced side walls connected to the bottom and rear walls and a door which define a storage compartment open at the up-

per end thereof. The intermediate sections each comprise a rear wall, a pair of spaced side walls connected to the rear wall, and a door which defines a storage compartment open at the top and bottom and having the same horizontal dimensions as the compartment in the base section. The top may be removably clamped to the upper end of the base section to close the compartment therein, or an intermediate section may be removably clamped to the upper end of the base section and then the top removably clamped to the upper end of the intermediate section. The bottom of the top section has a shallow upwardly extending recess therein which is adapted to register with the upper end of the storage compartment in the base section or an intermediate section. If more than one intermediate section is used they are removably clamped together and to the base section, and the top is then removably clamped to the upper end of the uppermost intermediate section. When intermediate sections are used the compartments therein align with each other and with the compartment in the base section to provide a single compartment of greater height and consequently greater storage capacity. By adding or subtracting intermediate sections the storage capacity of the refrigerator may be varied as desired to suit the requirements of a particular flight.

The base section has a closed chamber within the storage compartment which extends from the front to the rear of the compartment along one side wall and the bottom wall. Access is had to the chamber through a rectangular opening in the adjacent side wall. There is an air intake duct into the chamber through the lower end of the inner transverse wall of the chamber, and there is an air discharge duct which extends upwardly from the chamber along the adjacent side wall of the base section and terminates flush with the upper end of the side wall. Each intermediate section has a duct extending from the bottom to the top thereof along one side wall which are adapted to register with each other and with the duct in the base section.

The refrigerating mechanism is of conventional type and comprises the usual evaporator, compressor, condenser, storage tank and electric motor all of which are mounted upon a suitable platform which is adapted to seat upon the rails which extend out from under the base section. The refrigerating mechanism also includes a motor driven fan which is mounted in front of the evaporator in position to draw air through

and around the evaporator. When in operative position the evaporator and fan are disposed within the chamber in the base section, being insertable thereinto through the opening in the side wall of the base section. The platform also carries a plug door which closes the opening into the chamber. Suitable clamping means are provided to removably clamp the platform and the mechanism and door thereon in position. When it is desired to change the refrigerating mechanism the clamps are released and the platform and the mechanism carried thereby are moved outwardly as a single unit upon the rails until the evaporator is withdrawn from the chamber after which the unit may be carried away and a new unit installed.

Food is stored in the storage compartment upon a plurality of sheet metal trays which are slidably mounted upon suitable tracks which are secured to the side walls and extend from the front to the rear of the compartment. The peripheries of the trays are spaced from the walls of the compartment to provide unobstructed paths for the downward passage of air along the walls. The trays also have a plurality of slots therein through which air may flow. The slots in one tray are arranged to vertically align with the slots in the other trays to provide additional paths for the down flow of air.

In operation the fan draws air downwardly from the top of the compartment along the various paths and into the evaporator chamber through the air inlet port at the bottom of the chamber. The air is then drawn through the evaporator, where it is cooled, and forced up through the discharge duct into the shallow recess in the top section which diffuses the air over the top of the compartment. A continuous circulation and cooling of the air within the storage compartment is thus maintained.

The principal object of the invention is to provide a mobile refrigerator having a large storage capacity, but which is relatively light in weight and small in size as compared to the capacity thereof.

Another object of the invention is to provide a refrigerator of this type which is so constructed that the capacity thereof can be quickly and easily varied in accordance with particular requirements.

Another object of the invention is to provide a refrigerator of this type which will operate efficiently in either low or extremely high ambient temperatures.

Another object of the invention is to provide a refrigerator of the aforesaid type in which the refrigerating mechanism can be quickly and easily removed and replaced as a single unit.

Other and more limited objects of the invention will be apparent from the following specification and the accompanying drawings forming a part thereof in which:

Fig. 1 is a front elevation of a refrigerator, constructed according to our invention, showing the base section and the top section only being used to provide the minimum storage capacity;

Fig. 2 is a horizontal section taken on the line 2—2 of Figs. 1 and 4;

Fig. 3 is a horizontal section taken on the line 3—3 of Figs. 1 and 4;

Fig. 4 is a vertical section through the refrigerator as shown in Fig. 1 from side to side thereof, the plane of the section being indicated by the line 4—4 of Figs. 2 and 3;

Figs. 5 and 6 are vertical sections through the

refrigerator as shown in Fig. 1 from the front to the rear thereof, the planes of the sections being indicated by the lines 5—5 and 6—6 respectively on Fig. 4;

Fig. 7 is a view similar to Fig. 1 showing an intermediate section applied to the base section and the top section applied to the intermediate section in order to increase the storage capacity of the refrigerator;

Fig. 8 is a vertical section taken on the line 8—8 of Figs. 7 and 10;

Fig. 9 is a horizontal section taken on the line 9—9 of Figs. 7 and 10; and

Fig. 10 is a vertical section taken on the line 10—10 of Figs. 8 and 9.

Referring first to Figs. 1 to 6 of the drawing, in which the refrigerator of our invention is shown as adjusted for its minimum capacity, by reference characters, the numeral 1 indicates a base section, 2 a top section, and the numeral 3 indicates generally the refrigerating mechanism. The base section 1 comprises a bottom wall 4, a rear wall 5, and the side walls 6 and 7 which are all joined together to provide a storage compartment 8 which is open at the top and front thereof. The front of the compartment 8 is closed by a door 9 which is secured to the side wall 6 by hinges 10. The door 9 is held in closed position by a suitable latch 11 which is arranged to be released by a handle 12 which is disposed in a recess 13 in the front of the door. The walls 4, 5, 6 and 7 and the door 9 are all made up of spaced inner and outer sheet metal casing 14 and 15 with the space therebetween packed with suitable insulating material 16. The forward edges of the walls 4, 6 and 7 and the upper edges of the walls 5, 6 and 7 are all faced with thin strips 17 of plastic material such as "Bakelite." A sealing gasket 18 of heat-insulating material is secured to the inner face of the door 9 in position to tightly seal the front of the compartment 8. The top of the compartment 8 is closed by the top section 2 which is removably secured in place by clamps 19 and dowel pins 19a carried by the side walls 6 and 7. The top section 2 is made up of the spaced upper and lower sheet metal walls 20 and 21 which are connected together by the sheet metal peripheral wall 22. The space between the walls is packed with insulating material 23, and the front of the top section 2 is faced with a thin strip 24 of plastic similar to the strips 17. The bottom of the top section 2 has an upwardly extending rectangular recess 26 formed therein which is adapted to register with the upper end of the storage compartment 8. A sealing gasket 25 of suitable heat insulating material is permanently secured to the upper edges of the walls 5, 6 and 7 over the facing strips 17 thereon.

60 A vertical sheet metal partition 30 extends upwardly from the bottom wall 4 and inwardly from the side wall 7 at the forward edges thereof. The inner edge of the partition 30 is connected to the rear wall 5 by a transverse vertical sheet metal partition 31, and the upper edges of the partitions 30 and 31 are connected to the rear walls 5 and the side wall 7 by a horizontal sheet metal partition 32. The partitions 30, 31 and 32 and the walls 5 and 7 define a chamber 33 within the storage compartment 8. Access is had to the chamber 33 through an enlarged rectangular opening 29 through the side wall 7. A horizontal sheet metal partition 34 which extends between the partition 31 and the walls 5 and 6 slightly above the bottom wall 4 provides an air

intake duct 35 into the chamber 33. Elongated slots 36 are provided in the partition 34 for the entrance of air into the duct 35. Some air can also enter the chamber 33 through an elongated slot 28 in the horizontal partition 32. A vertical sheet metal partition 37 which extends upwardly from the chamber 33 to the upper end of the base section 1 in slightly spaced relation to the side wall 7 provides an air discharge duct 38 from the chamber 33.

Food is stored in the compartment 8 upon a plurality of similar rectangular trays 40 which are slidably mounted upon tracks 41 which are secured to the wall 6 and the partitions 31 and 37 and extend from the front to the rear of the compartment 8. The tracks 41 are spaced from the wall 6 and the partitions 31 and 37 except at the ends 42 and 43 thereof which are offset to engage the wall or partitions and be secured thereto. The spacing of the tracks 41 from their supporting wall or partition provides uninterrupted paths along the wall 6 and partitions 31 and 37 for the downward flow of air. The inner edges of the trays 40 are spaced from the rear wall 5 by a pair of spaced parallel vertical ribs 44, to provide a path along the rear wall 5 for the downward flow of air. When the trays 40 are in position with the inner edges thereof in contact with the ribs 44, the forward edges of the trays terminate inwardly of the door 9 so that a path for the downward flow of air is also provided along the door 9. Latching means (not shown) are provided for locking the trays in position. The trays 40 have a plurality of spaced parallel elongated slots 45 therein which are so arranged that the slots in any tray are in vertical alignment with the slots in the other trays. Additional paths are thus provided for the downward flow of air. The slots 36 in the partition 34, and the slots 45 in the trays 40 are rimmed by upturned flanges 46. The base section 1 is mounted upon a pair of spaced parallel rails 47 which extend out from under the base section 1 beyond the side 7 thereof.

The refrigerating mechanism generally indicated by the numeral 3 is a conventional electric refrigerating mechanism which comprises the usual evaporator, compressor, condenser, refrigerant storage tank and motor which are mounted upon a platform 50 which is adapted to seat on and slide along the rails 47. All of the refrigerating mechanism with the exception of the evaporator are enclosed by a removable cover 51 having venting louvers 52 therein. The evaporator 53 is disposed within the chamber 33, being inserted thereinto through the opening 29 in the side wall 7. The opening 29 is closed by a plug door 54 which is also carried by the platform 50. The refrigerating mechanism also includes a motor driven fan 55 which is disposed between the evaporator 53 and the plug door 54 within the chamber 33. The platform 50 and the refrigerating mechanism and the plug door 54 are locked in position by a pair of releasable latches 56.

In operation the fan 55 draws air downwardly along the various paths described and into the evaporator or cooling chamber 33 through the intake duct 35. The air is then drawn through and around the evaporator 53, which cools it, and forced up through the discharge duct 38 into the recess 26 in the top section 2 which diffuses the cooled air over the top of the compartment 8. In this way a continuous circulation and cooling of the air within the refrigerator is

maintained. Conventional means (not shown) is provided for regulating the operation of the refrigerating mechanism in order to maintain the desired temperature within the storage compartment 8.

If the refrigerating mechanism 3 should become damaged or out of order it can be removed as a single unit by releasing the latches 56 and sliding the platform 50 back along the rails 47 until the evaporator has been removed from the compartment 33. The unit can then be taken away for repairs and a new unit placed upon the rails 47 and slid into position.

When it is desired to enlarge the storage compartment 8 the top section 2 is removed from the base section 1 and one or more intermediate sections are clamped to the top of the base section and then the top section 2 is clamped to the top of the uppermost intermediate section. Each intermediate section comprises a rear wall and two side walls which constitute extensions of the rear wall 5 and the side walls 6 and 7 of the base section 1. Each intermediate section also has its own door.

Reference will now be had to Figs. 7 to 10 of the drawings which show one intermediate section 60 interposed between the base section 1 and the top section 2. The section 60 comprises the rear wall 61, the side walls 62 and 63 and a door 64 which is secured to the forward end of the side wall 62 by hinges 65 and is held in closed position by latching means 46 which is actuated by a handle 67 disposed in a recess 68 in the front of the door 64. The construction of the walls 61, 62 and 63 and the door 64 is similar to the construction of the walls and door of the base section 1 in that they comprise inner and outer sheet metal casings 69 and 70 with the space therebetween packed with insulating material 71. The upper edges of the walls 61, 62 and 63 and the forward edges of the walls 62 and 63 are faced with plastic strips 72, similar to the strips 17 on the base section 1. The door 64 carries a sealing gasket 73 similar to the gasket 18 on the door 9, and a sealing gasket 74 similar to the gasket 25 is permanently secured to the upper ends of the walls 61, 62 and 63 over the facing strips 72. The forward ends of the walls 62 and 63 are connected together at the lower ends thereof by a sheet metal tie bar 75 which is also faced with a plastic strip 72. The intermediate section 60 is removably secured to the upper end of the base section 1 by the clamps 19 and the dowel pins 19a carried by the base section. The top section 2 is removably secured to the intermediate section 60 in position to close the upper end thereof by clamps 76 and dowel pins 77 carried by the intermediate section 60. A vertical sheet metal partition 80 which extends from the bottom to the top of the intermediate section 60 in closely spaced relation to the side wall 63 defines an air discharge duct 81 which registers with and constitutes an extension of the air discharge duct 38 in the base section 1. Trays 40 are slidably supported in the intermediate section 60 upon tracks 82 which are identical in construction and installation with the tracks 41 in the base section 1. The intermediate section 60 thus constitutes an upward extension of the base section 1 and the storage compartment 8 therein, and increases the capacity of the storage compartment 8 by the capacity of the intermediate section. If still further capacity is required, additional inter-

mediate sections may be interposed between the base section 1 and the top section 2.

From the foregoing it will be apparent to those skilled in this art that we have provided a very simple and efficient mechanism for accomplishing the objects of the invention.

It is to be understood that we are not limited to the specific construction shown and described herein as various modifications may be made therein within the scope of the appended claims.

What is claimed is:

1. A refrigerator comprising a bottom section having a bottom wall, a rear wall, two side walls and a door defining a storage compartment open at the upper end thereof, a top section removably secured to the upper end of said bottom section in position to close the upper end of said storage compartment, partitions in said storage compartment defining a chamber at a lower corner of said storage compartment, an air inlet from said compartment into said chamber, an air outlet from said chamber into said storage compartment, a refrigerating mechanism including an evaporator and a fan, said evaporator and fan being disposed within said chamber and said fan being operative to induce a flow of air from said compartment into said chamber through said inlet and past said evaporator and out through said outlet back into said compartment, a plurality of trays disposed in said storage compartment, and means by which said trays are removably supported in vertically spaced relation in said storage compartment with the peripheral edges thereof spaced from the bounding walls of said compartment to provide uninterrupted paths for the downward flow of air along the inner faces of said bounding walls.

2. A refrigerator as defined in claim 1 in which each of said trays has a plurality of elongated slots therein, the slots in one tray being disposed in vertical alignment with the slots in the other trays to provide additional paths for the downward flow of air.

3. A refrigerator comprising a bottom section having a bottom wall, a rear wall, two side walls and a door, an intermediate section having a rear wall, two side walls and a door, said intermediate section being removably secured to the upper end of said bottom section with the rear and side walls thereof in vertical alignment with the rear and side walls of said bottom section, the said walls and doors of said bottom section and said intermediate section defining a storage compartment open at the upper end thereof, a top section removably secured to the upper end of said intermediate section in position to close the upper end of said compartment, partitions in said storage compartment defining a chamber at a lower corner of said storage compartment, an air inlet from said compartment into said chamber, an air outlet from said chamber into said storage compartment, a refrigerating mechanism including an evaporator and a fan, said evaporator and fan being disposed within said chamber and said fan being operative to induce a flow of air from said compartment into said chamber through said inlet and past said evaporator and out through said outlet back into said compartment, a plurality of trays disposed in said storage compartment, and means by which said trays are removably supported in vertically spaced relation in said storage compartment with the peripheral edges thereof spaced from the bounding walls of said compartment to provide uninterrupted paths for the downward flow of air along the inner faces of said bounding walls.

4. A refrigerator as defined in claim 3 in which each of said trays has a plurality of elongated slots therein, the slots in one tray being disposed in vertical alignment with the slots in the other trays to provide additional paths for the downward flow of air.

5. A refrigerator comprising a bottom section having a bottom wall, a rear wall, two side walls and a door defining a storage compartment open at the upper end thereof, a top section removably secured to the upper end of said bottom section in position to close the upper end of said storage compartment, a vertical partition extending upwardly from said bottom wall and forwardly from said rear wall and a horizontal partition extending forwardly from said rear wall between the upper end of said vertical wall and one of said side walls, said partitions defining a chamber within said storage compartment, a second horizontal partition extending between said vertical partition and the other of said side walls in slightly spaced relation to said bottom wall and defining an air inlet duct from the bottom of said storage compartment into said chamber, a second vertical partition extending upwardly from said horizontal partition in slightly spaced relation to the said one of said side walls and defining an air discharge duct from said chamber into the upper end of said storage compartment.

6. A refrigerator as defined in claim 5 in which each of said trays has a plurality of elongated slots therein, the slots in one tray being disposed in vertical alignment with the slots in the other trays to provide additional paths for the downward flow of air.

7. A refrigerator comprising a bottom section having a bottom wall, a rear wall, two spaced side walls and a door defining a storage compartment open at the upper end thereof, a vertical partition extending upwardly from said bottom wall and forwardly from said rear wall and a horizontal partition extending forwardly from said rear wall between the upper end of said vertical wall and one of said side walls, said partitions defining a chamber within said storage compartment, a second horizontal partition extending between said vertical partition and the other of said side walls in slightly spaced relation to said bottom wall and defining an air inlet duct from the bottom of said storage compartment into said chamber, a second vertical partition extending upwardly from said horizontal partition in slightly spaced relation to the said one of said side walls and defining an air discharge duct from said chamber into the upper end of said storage compartment, an intermediate

section having a rear wall, two spaced side walls, a door and a vertical partition which is slightly spaced from one of said intermediate side walls and defines an air discharge duct in said intermediate section, said intermediate section being removably secured to the upper end of said bottom section with the rear and side walls thereof in vertical alignment with the rear and side walls of said bottom section and the discharge duct therein in register with the discharge duct in said bottom section, a top section removably secured to said intermediate section in position to close the upper end thereof, a refrigerating mechanism including an evaporator and a fan, said evaporator and said fan being disposed within said chamber and said fan being operative to induce a flow of air from the lower end of said storage compartment through said inlet duct into said chamber and past said evaporator and out from said chamber through said discharge duct into the upper end of said storage compartment, said refrigerating mechanism being mounted upon a platform which is removably secured to one of the walls of said bottom section.

8. A refrigerator comprising a bottom section having a bottom wall, a rear wall, two spaced side walls and a door defining a storage compartment open at the upper end thereof, a vertical partition extending upwardly from said bottom wall and forwardly from said rear wall and a horizontal partition extending forwardly from said rear wall between the upper end of said vertical wall and one of said side walls, said partitions defining a chamber within said storage compartment, a second horizontal partition extending between said vertical partition and the other of said side walls in slightly spaced relation to said bottom wall and defining an air inlet duct from the bottom of said storage compartment into said chamber, a second vertical partition extending upwardly from said horizontal partition in slightly spaced relation to the said one of said side walls and defining an air discharge duct from said chamber into the upper end of said storage compartment, an intermediate section having a rear wall, two spaced side walls, a door and a vertical partition which is slightly

spaced from one of said intermediate side walls and defines an air discharge duct in said intermediate section, said intermediate section being removably secured to the upper end of said bottom section with the rear and side walls thereof in vertical alignment with the rear and side walls of said bottom section and the discharge duct therein in register with the discharge duct in said bottom section, a top section removably secured to said intermediate section in position to close the upper end thereof, a refrigerating mechanism including an evaporator and a fan, said evaporator and said fan being disposed within said chamber and said fan being operative to induce a flow of air from the lower end of said storage compartment through said inlet duct into said chamber and past said evaporator and out from said chamber through said discharge duct into the upper end of said storage compartment, a plurality of trays disposed in said storage compartment, and means by which said trays are removably supported in vertically spaced relation in said storage compartment with the peripheral edges thereof spaced from the bounding walls of said compartment to provide uninterrupted paths for the downward flow of air along the inner faces of said bounding walls.

9. A refrigerator as defined in claim 8 in which each of said trays has a plurality of elongated slots therein, the slots in one tray being disposed in vertical alignment with the slots in the other trays to provide additional paths for the downward flow of air.
